UNITED STATES PATENT OFFICE.

EIDE H. HINNERS, OF NEW YORK, N. Y.

IMPROVEMENT IN CUTTER-HEADS FOR MOLDINGS.

Specification forming part of Letters Patent No. **140,626**, dated July 8, 1873; application filed December 14, 1872.

To all whom it may concern:

It is known that I, E. H. HINNERS, of the city, county and State of New York, have invented a new Improvement in Cutter-Heads for Molding, of which the following is a specification:

The object of my invention is to produce a rotary cutter-head for making moldings with a rabbet at one side, separated from the molding by a narrow strip too thin and weak to sustain the strain to which it would be subject if the rabbet was formed with the ordinary rotary planing-cutter; and it consists of a staggered saw attached to the cutter-head of the molding-planer to form the rabbet.

Figure 1 is a side elevation of the cutter-head, such as I propose to employ, and Fig. 2 is an end elevation.

Similar letters of reference indicate corresponding parts.

The molding, such as I wish to produce, is shown dotted in section in Fig. 1, wherein D represents the rabbet and E the thin strip of wood I wish to leave between it and the molding. This thin strip would not have strength to resist the tendency of the cutters to split off from the main portion of the wood if the ordinary planing-cutters were used both for

the molding and the rabbet, but as the planing-cutters must be used for the molding I therefore make a cutter-head for producing this work of a stock, A, with molding-cutters B, and a staggered saw, C, all as represented in the drawing, and thus considerably lesscn the splitting-strain on the strip E, as the saw has much less of such effect than the planing-cutters have.

I am aware that similar cutter-heads have been long known to the public, and some possessing many of the general characteristics which are to be found in mine, but none exhibiting the special feature now disclosed to the public by me.

Having thus described my invention, I claim as new and desire to secure by Letters Patent—

A cutter-head consisting of the molding-cutters B and staggered saw C, arranged on the cutter-head A to form a rabbet, D, separated from the molding by a narrow strip, E, substantially as represented in the drawing.

E. H. HINNERS.
